OIL-SEAL PULLER TOOL

Roy N. Bowden, 42 E. Shore Drive, Indian Lake,
Denville, N.J.

Original design application Dec. 26, 1963, Ser. No. 77,932,
now Patent No. 201,302, dated June 8, 1965. Divided
and this application Mar. 9, 1965, Ser. No. 84,163

Term of patent 14 years

(Cl. D54—13)

FIGURE 1 is a side, isometric view of an oil-seal puller tool embodying my new design;

FIGURE 2 is a front, isometric view thereof; and

FIGURE 3 is a top, plan view thereof.

The dominant features of my design reside in the portions shown in full lines.

This application is a division of my copending application Serial Number D.77,932, filed December 26, 1963, entitled Oil-Seal Puller Tool, now Patent No. D.201,302.

I claim:

The ornamental design for an oil-seal puller tool, as shown and described.
